UNITED STATES PATENT OFFICE.

BERNHARD FRITZSCH, OF CINCINNATI, OHIO.

PHONOGRAPH SOUND BOX.

Application filed January 25, 1921. Serial No. 439,869.

To all whom it may concern:

Be it known that I, BERNHARD FRITZSCH, a citizen of the United States, and residing at Cincinnati, in the county of Hamilton and 5 State of Ohio, have invented a new and useful Improvement in Phonograph Sound Boxes, of which the following specification is a full disclosure.

My invention relates to an improved 10 sound-box for phonographs and the present invention is specifically an improvement over the sound-box disclosed in my prior Patent No. 1,217,294, Feb. 27, 1917.

More particularly the invention relates to 15 the construction and material of the diaphragm. My said prior diaphragm possessed a very superior tone quality, but being of wood it was subject to warping, contraction and expansion, and to non-uniform 20 elasticity. It was relatively flexible at one diameter and relatively less flexible at the transverse diameter, due to the grain of the wood.

The object of my present invention is to 25 retain the desirable tone characteristics of a wood diaphragm but without the objections stated. I therefore produce a diaphragm having a wood-like composition, but of uniform resilience. For this purpose, I prefer- 30 ably use a composition of matter comprising largely wood pulp, leather scraps, a small amount of rubber, and some binder as casein or lime. The material is finely ground, mixed and pressed in a wet state into about one- 35 sixteenth inch board thickness. This is hard, when dry, and wood-like, but not grained, and is uniformly flexible.

It is more desirable, constant and de- 40 pendable than wood.

The composition board is cut into disks and ground down to about a one-thirty-second inch thickness of uniform cross-section.

In the drawings:

Fig. 1 shows a face view of my diaphragm.

Fig. 2 a cross section of the same.

Fig. 3 an element of my complete sound- 50 box.

Fig. 4 is a central vertical section of the same.

The sound-box proper is conventional, hav- 55 ing the tone arm 1, and the usual diaphragm holder 2, and needle arm 3.

Preferably, the central portion of the wood composition disk 4 is formed with a 55 central orifice, and this opening is covered by a central disk 5 which is relatively less

resilient, and this minor disk is preferably made of wood, and of greater cross section than the composition portion 4 of the dia- 60 phragm. It is adhesively secured thereto and the needle arm is attached to the center of this small disk. Preferably, this disk 5 is placed on the outer surface of the dia- phragm, and the relative areas of the disk are indicated by the scale drawing indicat- 65 ing dimensions producing the best results.

I have found that the tone is very superior to the all wood or natural wood diaphragm, and that it has superior property of record- 70 ing or reproducing all overtones with dis- tinctness and naturalness. This is particu- 75 larly noticeable in piano and violin tones, in which the overtones are the most elusive. Comparison of this diaphragm with the one of my former patent, shows marked improve- 75 ment, for instance, in the piano bass notes, or in the violin harmonic tones, which is a recording and reproducing test of the most rigid character.

This diaphragm when dried, hard, and 80 varnished is secured in the holder in the usual manner.

Having tried a wide range of materials adaptable, I have found best results in the diaphragm composed and constructed as di- 85 closed. This diaphragm is about as tone neu- tral as it is possible to constitute, and hence does not by its own vibration, color the tones to be recorded or reproduced.

I do not desire to be limited to the exact 90 composition or to the exact ingredients or proportions. Neither do I desire to be lim- ited to the specific structure, since in the light of this disclosure, the principles inher- 95 ing in this discovery may be understood and reduced to practice with some considerable latitude.

Having described my invention, I claim:

A diaphragm for the sound box of a pho- 100 nograph consisting of a composition matter comprising wood pulp, leather, a small amount of rubber and binding agents, formed into a hard, non-grained and uniformly re- silient disk, adapted to be secured in a sound- 105 ing box.

In witness whereof, I hereunto subscribe my name, as attested by the two subscribing witnesses.

BERNHARD FRITZSCH.
